RECTAL DILATOR

Addington C. Tedford, Huntington, W. Va.

Application June 11, 1945, Serial No. 598,851

1. Claim. (Cl. 128—345)

1.

This invention relates to a rectal dilator.

A primary object of this invention is the provision of an improved device for dilating the rectum for the purpose of massaging or stretching the sphincter muscle.

An additional object of the invention is the provision of such a device which will dilate the sphincter muscle naturally from the interior portion of the rectum.

Another object of the invention is the provision of such a device characterized by a substantial minimum of parts readily disassemblable in such manner that the instrument may be readily cleaned.

Other objects of the invention will in part be obvious and in part be pointed out as the description of the invention proceeds, and shown in the accompanying drawing, wherein there is disclosed a preferred embodiment of this inventive concept.

In the drawing:

Figure 1 is a longitudinal sectional view taken substantially along the center line of one form of device embodying features of the instant inventive concept.

Figure 2 is an end elevational view of the device disclosed in Figure 1, as viewed from the left.

Figure 3 is an end elevational view of the device as viewed from the right.

Figure 4 is a plan view of a constructional detail.

Figure 5 is a view similar to Figure 3 but showing a modified form of construction.

Figure 6 is a fragmentary longitudinal sectional view similar to Figure 1 but showing a further modified form of construction.

Having reference now to the drawing, wherein similar reference characters denote similar parts, there is shown at 10 a plate provided with four radial bifurcated portions 11, between which are adapted to be pivotally mounted, as by means of pivot pins 12, extending portions 13 of dilator members 14. The dilator members 14 of the preferred embodiment comprise sectors forming a substantially conical member adapted to be inserted in the rectum.

The outer extremities of the members 13 are bent inwardly, as shown at 15 and terminate in projecting lugs 16 which are adapted to extend through arcuate slots 17 in a circular plate 18. The slots 17 are offset from the center of the plate 18 in such manner that as the plate 18 is turned, the lugs 16 are moved toward and away from the center of the plate, which movement serves to expand or contract the members 14, the

2.

pivot pins 12 serving as fulcrums for the movement thereof.

The plate 18 is provided with a centrally positioned aperture 19 through which extends a screw 20 provided with a head 21, the extremity of the screw engaging in a threaded aperture 22 centrally located in the base plate 10.

As shown in Figure 1, a spacer sleeve 26 embraces the bolt 19 and lies between the plate 10 and the plate or knob 18. The spacer thus assures that the bolt 19, while securely holding the members 10 and 18 together, will positively prevent the bolt from pressing member 18 against the ends of members 13 with a resultant binding action.

Thus, it will be seen that the screw 20 serves to hold the parts in related assembly, and that rotation of the plate 18 serves to dilate the conical member comprised of the sectors 14.

Figure 5 discloses a modified form of construction, wherein the members 14', which take the form in cross-section of sectors of a circle, are of substantially less thickness than the previously disclosed members 14, this form of device being particularly adaptable to use for children.

Referring now to the modification disclosed in Figure 6 there is shown at 10' a plate substantially identical with the plate 10 and provided with four radial bifurcated portions 11' between which are adapted to be pivotally mounted, as by means of pivot pins 12', extending portions 13' of dilator members 14'' which members are substantially identical to dilators 14.

Extending portions 13' are bent inwardly to form substantially right angle portions terminating in bulbous extremities 16'. A bolt 20' provided with a head 21' is adapted to extend outwardly through a recess 22' in the center of plate 10', and has positioned thereabout a coil spring 23 which engages the bulbous extremities 16'.

The operation of this modification should be equally obvious in that as the nut 25 is rotated in a direction to cause the same to move toward the plate 10', the bulbous extremities 16' will be forced inwardly against the pressure exerted by the spring 23 to cause dilation of the members 14''. Conversely as the nut 25 is rotated in the opposite direction, the bias of the spring 23 against washer 24 serves to retract the dilator members 14'' to normal position.

In the operation of each form of the device, it will be readily understood that the members 14, 14' or 14'' in contracted position may be inserted in the rectum and subsequently expanded by rotation of the plate 18 or nut 25, which rotation

will expand the members 14, or 14" which in turn, due to their configuration, will serve to expand the sphincter muscle from within the interior of the rectum.

From the foregoing, it will now be seen that there is herein provided a device accomplishing all the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

A dilator comprising a base plate, a plurality of bifurcated lugs extending from said plate, a plurality of extending members pivotally secured in said bifurcated lugs, said extending members forming sectors of a cone, each of said extending members having a longitudinally disposed

5 projection at the end thereof, a rotatable knob disposed parallel to said plate and journaled thereon, said knob having arcuate cam slots therein, said projections extending into said cam slots for expanding said conical sectors in response to rotation of said knob, a spacer between said knob and said plate and a bolt securing said knob to said plate and extending through said spacer.

ADDINGTON C. TEDFORD.
